AMPLIFICATION WITH HIGH EFFICIENCY

James W. McRae, Neptune, N. J., assignor to
 Bell Telephone Laboratories, Incorporated, New
 York, N. Y., a corporation of New York

Application August 15, 1940, Serial No. 352,722

8 Claims. (Cl. 179—171)

The present invention relates to power amplifier circuits for radio transmission or similar purposes, with special provision for reducing distortion and increasing efficiency of operation.

A feature of the invention is the use of an electron multiplier type of amplifier as a power amplifier, with circuit provisions for reducing distortion and increasing efficiency.

Electron multipliers, as is known, permit of very large gains and have the advantage of not requiring electrodes of individual stages to be maintained at alternating current potentials. This makes them especially suited to high frequency amplification. Moreover, one of their characteristics is that the anode potential of the final or output stage has practically no effect on the anode current, at least in the normal operating range. This fact is favorable to the transmission through the multiplier of short pulses of current which retain their form under nearly complete control of the input circuit. The use of the short pulses permits high efficiency to be obtained in the output stage which couples to the load.

Where the input signal to the first stage is a modulated carrier wave or where modulation takes place anywhere ahead of the output multiplier stage, a feature of the invention is a control of the final anode voltage in accordance with the envelope of the modulated wave in such manner as to keep the average anode voltage approximately the same as the instantaneous peak alternating voltage in order to reduce dissipation of energy in the space path of the final stage.

The invention also comprises as features the use of overall negative feedback at radio frequency and, therewith or separately, envelope frequency feedback around the initial stage to reduce noise and distortion.

These and the other features and the various objects of the invention will appear more fully from the following detailed description taken in connection with the accompanying drawings in which:

Fig. 1 is a schematic circuit diagram of one form of electron multiplier system incorporating the invention;

Figs. 2, 3, 4 and 5 show wave forms to be referred to in describing the operation;

Fig. 6 is a partial diagram of a circuit, which may be substituted for that portion of Fig. 1 to the right of the broken line 6—6;

Fig. 7 is a schematic circuit diagram of two electron multipliers in a system embodying the invention in one form; and

Fig. 8 is a partial diagram of a circuit, which may be substituted for that portion of Fig. 1 to the left of the broken line 8—8.

Referring to Fig. 1, an electron multiplier tube 1 is connected to amplify waves received through an input connection 2 and to impress the amplified output on a tuned output or tank circuit 3 which may comprise a load or to which any suitable load 4 is coupled, such as an antenna or sending circuit.

The electron multiplier tube 1 of itself forms no part of the present invention but may be of any suitable construction, the preferred construction being in accordance with the disclosure in my copending application Serial No. 371,124, filed December 21, 1940.

As illustrated herein the multiplier comprises a succession of suitably arranged and suitably treated emitting surfaces 5, 6, etc. with an input or starter section comprising cathode 7, control grid 8, accelerating grid 9 and first emitter plate 5, and with an output section or anode region comprising final emitter 10, positive grid 11 and anode 12. A suitable direct current supply source shown in the form of battery 13 applies steady positive voltage to the emitters, increasing in value from emitter to emitter throughout the tube. A voltage divider or potentiometer 14 may be used for applying the potentials to some of the emitter plates. In the case of the later stages which draw more power from the supply it may be advantageous to use sections of the battery as indicated in the diagram. It would be obvious to employ other types of voltage supply in view of known practice. The emitter plates are by-passed to ground through large condensers 19.

The starter section includes an input circuit comprising the control grid 8, input coupling 15, bias battery 16 and cathode resistor 17 which is shown shunted by capacity 18 (which may be omitted where not necessary) and cathode 7. This section includes an output circuit comprising first emitter plate 5, portion of resistor 14, cathode network 17, 18 and cathode 7. The battery 16 applies such a large negative potential to the grid that class B or class C operation is secured. That is, transmission through the starter section consists of pulses of half cycle or smaller duration.

In the case of a modulated high frequency input wave at 2, the cathode network 17, 18 is preferably adjusted to vary the control grid bias at the envelope or signal frequency. Rectification in the plate circuit of the starter section

causes a detected current of the signal frequency to flow through resistance 17, thus producing a varying grid bias which permits only the positive tips of the high frequency wave to be transmitted. For this use, condenser 18 acts as a radio frequency by-pass. At the same time, resistance 17 and condenser 18 provide negative feedback at the signal frequency. This negative feedback compensates for distortion in the starter section and the varying bias provides the short impulses that are favorable for securing highly efficient operation of the output or anode section as will be described later.

Grid 8 is biased to a positive potential to accelerate electrons toward the emitter 5. Condensers 20, 21 are blocking or by-pass condensers.

In the output or anode section the final emitter 10 is at direct current ground. Screen 11 is positive with respect to emitter 10, and anode 12 is maintained at average potential more positive than that of screen 11 by the lead 24 extending to the power supply rectifier circuit generally indicated at 25. Lead 24 includes filter choke 26 and filter condensers 27, 27.

A negative feedback connection is made through lead 51, stopping condensers 52, and loss network 53, which may be adjustable, from anode 12 to control grid 8 for producing large negative feedback for reducing noise and distortion in the multiplier in accordance with the teachings of Black Patent 2,102,871, December 21, 1937.

The power supply circuit 25 comprises a six-phase rectifier system including mercury vapor rectifier tubes 29 having their cathodes connected in common to filter choke 26 and their anodes connected to individual windings of a six-phase secondary 30 provided with a three-phase primary 31 connected to 60-cycle three-phase supply line 32, in accordance with usual power circuit practice. In order to control the voltage that is applied to the anode 12 of the multiplier, there is provided a phase controlling system comprising the two phase shifting tubes 33 and 34 which serve to control the phase of the 60-cycle grid excitation of the tubes 29 by way of the three-to-six phase transformer 35. The grids of tubes 29 are individually connected to windings of the six-phase secondary through limiting resistors 36.

The use of tubes such as 33 and 34 in combination with tubes 29 to control a terminal voltage is, in and of itself, old and well known in the art. In the present case the phase shifting tubes 33 and 34 are under control of the output current of direct current amplifier 38 or 38' depending upon the position of switch 55, in a manner and for a purpose to be described presently. As the voltage from amplifier 38 varies, with switch 55 in the position shown, the internal resistance of tubes 33, 34 is varied and the magnitude of this resistance relative to the fixed value of capacity 39 or 40 causes a shift in phase of the waves applied through transformers 41 and 42 with respect to the waves appearing across respective circuits 43 and 44 leading to the transformer 35. In this way the grid waves in tubes 29 are advanced or retarded in phase with respect to the waves applied to the anodes of tubes 29 so that current is allowed to flow through tubes 29 for a greater or less fraction of the positive half cycle of plate potential. The effect of this is to vary the current flowing through inductance 26 into the capacity 27, which has a capacity value with respect to the other circuit

constants such as to permit voltage changes of signal frequency to be developed and to be applied to the anode 12. The manner in which this voltage is controlled will now be described.

5 The screen 11 in the multiplier is connected through inductance 47 and resistance 48 to battery section 49 and as stated has a positive voltage of average value less than that of the anode 12. During the negative radio frequency swing of the voltage of anode 12, if the anode falls to sufficiently low voltage, a portion of the current emitted from plate 10 will flow to the screen 11 producing a drop of potential across elements 47 and 48 which is applied to the input 10 of amplifier 38 after filtering at 50. In this way the phase shift tubes 33 and 34 are controlled to, in turn, control the average voltage of the anode 12 through the medium of the rectifier circuit 25 as described. The proper number of 15 stages must be used in amplifier 38 to produce the correct phase relation between the voltage drop appearing across 47 and 48 and that applied to the grids of tubes 33 and 34.

Referring to Fig. 2, the radio frequency voltage 25 of the anode 12 is shown and also the average voltage of anode 12 in the absence of the control exerted through the rectifier 25 by the phase controlling tubes 33, 34. The average value remains the same for unmodulated and 30 modulated waves and is indicated at E, Fig. 2. Fig. 4 shows the anode current pulses which are indicated as short sharp impulses occurring at the negative point of the anode voltage swing. Three values are shown corresponding to (1) the 35 unmodulated condition, (2) the modulated condition corresponding to a negative swing of the signal wave and (3) the modulated condition corresponding to a positive swing of the signal wave. The corresponding voltages existing between the plate 10 and anode 12 when these currents are passing are shown in Fig. 2 at E₁, E₂ and E₃. E₁ and E₂ represent inefficient operation since the E x I loss is considerable.

Operation with the control of the average anode voltage according to the invention is illustrated by Fig. 3 where the average anode voltage changes in proportion to the radio frequency peak voltage or approximately so and is shown as having the three values E', E'' and E'''. The 45 instantaneous voltage at the time the current is flowing is seen to be about the same in all cases and of about the value E₃ of Fig. 2, for illustration. The average voltage of grid 11 is shown as E_g and it will be noted that the average voltage of the anode 12 is always adjusted so that the minimum peaks dip just below the value E_g. During the instants when the anode voltage is lower than the grid voltage, current flows as indicated in Fig. 5, of an average magnitude such as to determine the corresponding average anode voltages E', E'' and E''' for the three illustrated conditions. In the absence of any grid current, the rectifier 25 would tend to supply minimum average anode voltage and this would result in production of grid current flow which would in turn tend to raise the average anode voltage until a condition of balance were reached. Increase of grid current causes increase of anode average voltage and decrease 55 of grid current causes decrease of anode average voltage. The result is a condition somewhat similar to that indicated in Fig. 3 such that the minimum value of the anode voltage swing for all conditions of modulation and for the unmodulated condition is held to about the same value,

Just below the average voltage of screen 11. The tube losses in the output section are therefore kept to a minimum.

Since a voltage of the signal frequency is developed across the cathode resistor 17, this voltage may be used to control the phase shifting tubes 33 and 34 if desired. For this purpose switch 55 is thrown to its alternate contact connecting the output of amplifier 38' to the grids of tubes 33 and 34. The input of amplifier 38' is connected across resistor 17. A reverse potential may be applied to a suitable part of the amplifier 38', if necessary, to counteract to the required extent the off-ground steady potential of the resistor 17. It is necessary to use the proper number of stages in amplifier 38' so that the correct phase relation will be obtained between the voltage drop appearing across resistor 17 and the voltage applied to the grids of tubes 33 and 34.

With this circuit modification, as the pulses of current flowing through resistor 17 increase in amplitude under control of the input wave, the rectifier circuit 25 is controlled to increase the average anode voltage, and as these pulses decrease in amplitude the average anode voltage is decreased in corresponding manner. The result is similar in general to that described above in connection with the curves in Figs. 2, 3 and 4 but in this case no use is made of the grid current pulses of Fig. 5.

An alternative form of circuit for controlling the final anode voltage is shown in Fig. 6 in which the circuit portion (not shown) at the left of the broken line 6-6 is assumed to be the same as the corresponding portion of Fig. 1. The three-phase supply 56, which could, if desired, be a single phase supply instead, is connected to rectifier 57 the positive output terminal of which is connected through reactor 58 to the anode 12 of the multiplier output section. The reactor 58 may form part or all of the smoothing filter, additional series inductance being provided if necessary. Filter condensers 27 are provided as before. The reactor includes saturating windings 59 and secondaries 60 which are included in series in the primary leads. With small current in windings 59 large inductance is developed in the input of the rectifier and with large current in the saturating windings the series input inductance is reduced.

As anode 12 draws more average current the action of the variable reactor 58 is to increase the supply voltage on account of the lowered inductive reactance in the rectifier input. Conversely, small current to the anode 12 results in reducing the voltage supplied to the anode. In this case the linearity of the control is not as good as in the Fig. 1 circuit so that it is preferable not to allow the minimum instantaneous voltage of anode 12 to fall low enough to produce current flow in the circuit of grid 11. This method of control has the advantage of simplicity, however, over that of Fig. 1.

In Fig. 7 two electron multipliers 65 and 66 are associated together to form a Doherty amplifier of the general configuration disclosed in British Patent 471,423 and in U. S. Patent 2,210,028, granted August 6, 1940, but using electron multipliers in place of triodes. These may be of any suitable type but are shown as of the same type as those of Fig. 1 except that in this case the circuits for controlling the anode voltage at the speech rate are omitted.

The input waves, which may be signal modu-

lated radio frequency waves or other type, are applied across the input coupling resistor 67. From this they are applied to the multiplier inputs in parallel, a quarter wave-length line 68 being inserted in the input to multiplier 66, in accordance with the Doherty disclosure. Self-bias is shown for the starter section of each multiplier comprising cathode resistor 17 and bypass condenser 18, and the input circuit is coupled in each case through a series capacity 69, the inductance 70 being a radio frequency choke.

The operation of the bias in giving signal frequency negative feedback around the starter section is similar to that of Fig. 1. It is also within the invention to use fixed bias obtained, for example, from a battery.

The outputs of the multipliers 65 and 66 are connected to the output circuit or load 72 which may be a tuned circuit, such as an antenna, or 20 may be of other type. Alternatively this load may be the input of a succeeding amplifier stage and may be untuned. The voltage for the final anode of each multiplier is obtained from suitable supply 73 such as a rectifier to which connection is made by way of radio frequency choke 74. The quarter wave-length line 71 is inserted 25 between the output of multiplier 65 and the load in accordance with the teachings of the Doherty patent. Feedback connection 51 provides negative feedback around the two multipliers for increasing the linearity of the circuit.

The electron multipliers are especially suited to use in a Doherty circuit because of their high gain and ability to operate with short pulse excitation.

The high gain makes possible modulation at low power level and the short pulse operation results in high efficiency. Moreover, as pointed out above, the lack of tuned interstage circuits in the multiplier makes possible large gain with preservation of the wave form of the pulses and the negative feedback also increases the linearity of the amplifier.

The circuit of Fig. 7, therefore, also represents a system in which there is a control circuit, in this case in the form of auxiliary multiplier 66, whereby the efficiency of the main amplifier is prevented from varying as the amplitude of the modulating signal changes, at least for a considerable portion of the modulation cycle.

A further way of compensating distortion in the multiplier is by use of predistortion of appropriate type. One circuit that may be used for this purpose is shown for illustration in Fig. 8. In this figure the signal input is at 82 and the signal passes through input coil 83 to the grid of tetrode 84 by which it is amplified. The output of tube 84 is coupled by a resistance-capacity circuit to the grid 8 of the multiplier 1. The series coupling capacities are at 86 and 89 and the shunt resistance consists of 85, 88, 90 and the internal resistance of diode 87, which latter resistance is variable depending upon the voltage applied across it. Batteries 91 and 92 supply steady potentials to the anode and screen grid of tube 84 and to the diode, respectively.

The distortion in the starter section of the multiplier is due to its curved grid voltage-plate current characteristic. By adjusting resistances 85 and 88 to the right values the non-linearities of the tetrode and diode can be made to compensate the distortion in the multiplier, especially that occurring in the starter section.

The scheme is not limited to the use of a tetrode and a diode. Apparatus of reasonably

equivalent performance may be used. For example, solid element non-linear resistances such as rectifiers may be used in place of the diode. One such element would be copper-oxide.

The invention is not to be construed as limited to the detailed circuit arrangements disclosed since the invention itself may take on widely different embodiments. The scope of the invention is defined in the claims which follow.

What is claimed is:

1. In combination with an electron multiplier device comprising a succession of emitter plates and an anode or output electrode, a resonant load circuit coupled to said anode, means transmitting short unidirectional current impulses through said multiplier and into said load circuit in synchronism with the fundamental frequency oscillations in said circuit, means to cause said impulses to vary in amplitude in accordance with information to be transmitted, a source of anode voltage, and means controlled by said impulses of current for varying the voltage of said source in correspondence with the variations in amplitude of said impulses.

2. In combination with an electron multiplier having a primary or starter section and an output section, means to apply a signal modulated high frequency wave to said starter section, distortion compensating means comprising means to produce negative feedback at the signal frequency around said starter section and distortion reducing and noise reducing means comprising an over-all negative feedback path for the high frequency waves from the output side of said output section to the input side of said starter section.

3. The combination according to claim 2 in which said starter section has a non-linear transmission characteristic tending to produce distortion, comprising in combination therewith a predistorting circuit included in said means to apply the signal modulated high frequency wave to said starter section, said predistorting circuit having a transmission characteristic of such form as to counteract said distorting tendency of said starting section.

4. In combination, a space discharge device having an electron emitting cathode, an anode and a grid, means to apply steady positive potentials to said anode and grid with respect to said cathode, a tank circuit coupled to said anode and cathode, means to control said device in accordance with an input wave to produce signal modulated pulses of current between said cathode and anode at the fundamental frequency of said tank circuit, each pulse of a duration short compared with a half period of the fundamental frequency wave of said tank circuit, said positive grid receiving a portion of the space current at the instant of minimum voltage swing, and means controlled by said grid current for varying the average voltage of said anode to improve the efficiency of said device.

5. In combination, a source of signal modulated high frequency input waves, a utilization circuit, an amplifier comprising a multistage electron multiplier having an input terminal coupled to said source and an output stage comprising an emitter and an anode coupled to said

utilization circuit, a source of positive voltage connected to said anode, means biasing said multiplier to cause the modulated wave to be transmitted by said output stage in short impulses of current of a duration small compared with the high frequency wave period whereby the efficiency of said stage is high for large ratio of high frequency to direct voltage between said emitter and anode, and means controlled by said signal modulated wave for increasing the efficiency of said output stage when the high frequency voltage on the anode has amplitudes corresponding to the unmodulated carrier and smaller amplitudes.

6. In combination with an electron multiplier having a succession of multiplier sections and an output section comprising the last emitter, a screen and an anode, means to apply positive potentials to the screen and anode, means to transmit high frequency pulses of current through said multiplier and to modulate said pulses in accordance with signals before they are impressed on said output section, circuit means for deriving from electrodes of said multiplier a rectified component of said modulated pulses, means to isolate the signal component thereof and means controlled by said isolated signal component for varying the positive potential applied to said anode to increase the operating efficiency of said output section.

7. In combination with an electron multiplier having a succession of multiplier sections and an output section comprising the last emitter plus a screen and an anode, a source of direct current supply for energizing said multiplier sections including means to apply positive potentials to said screen and anode, means to transmit high frequency pulses of current through said multiplier and to modulate the pulses so transmitted in accordance with signals, whereby certain of the electrodes of said multiplier including said anode and said screen draw current from said supply source in pulses of varying amplitude, and means controlled by the current drawn by certain of said electrodes for varying the voltage applied to said anode at the signal frequency, said last means causing an increase in the current so drawn to increase the voltage applied to said anode.

8. In combination, a source of signal modulated high frequency input waves, a utilization circuit, an amplifier comprising a multistage electron multiplier having an input terminal coupled to said source and an output stage comprising an emitter and an anode coupled to said utilization circuit, a source of positive voltage connected to said anode, means biasing said multiplier to cause the modulated wave to be transmitted by said output stage in short impulses of current of a duration small compared with the high frequency wave period, whereby the efficiency of said stage tends to vary throughout the modulation cycle dependent upon the instantaneous amplitude of the modulating signal, and space discharge means controlled by said signal modulated wave for controlling the voltage across said output stage to maintain the efficiency of said output stage constant for at least a portion of the modulation cycle.

JAMES W. MCRAE.
